NONDRIP BOTTLE

Howard J. Whelan, Baltimore, Md., assignor of thirty-five per cent to Richard E. Tippett and twenty-five per cent to Frank H. Kelly, both of Baltimore, Md.

Application November 4, 1932, Serial No. 641,293

1 Claim. (Cl. 215—31)

This invention refers to bottles and more particularly to a so-called non-dripping bottle. It has among its objects:

To provide a bottle that will not allow the liquids poured from it, to run down the body of the bottle, when tipped to pouring position, but will cut the flow off with a clean cut;

To have a mouth on a bottle that will permit drops to be poured and counted, without the drops flowing down the side of the bottle;

To have a bottle adaptable for controlling the dropping process from a bottle in pouring;

To have such an arrangement provided, and yet permit the bottle to be readily and conveniently manufactured;

To provide for the general control of liquids from bottles;

To have such provisions that they will be suitable for liquid containers of many kinds, in addition to bottles (so-called) specifically, and many other objects that will become apparent as the invention is more fully set forth.

The existing types of bottles used for containing liquids of various kinds, and particularly those of a medicine nature, have the difficulty of causing liquids poured from them, to catch and flow down the body of the bottle. This in turn causes the bottle to become wet and spoils any labels that are mounted on it, because of the liquid running down them.

This difficulty is particularly prevalent in the bottles having moulded screw-threaded exterior mouth portions, and bottles that use caps of various kinds that are moulded to take the caps.

In this invention, the mouth of a bottle is provided with means for giving a control of the flow of liquid from it, which means may be at the extreme mouth or adjacent to it. The means is termed a non-drip feature and may be a part of the bottle material or added as an extra member to provide the desirable function. The use of this invention enables those using the bottles to measure drops or flow from the same with facility and accuracy, while at the time preventing the liquid flowing down the side of the bottle and spoiling the label or appearance of the bottle.

In the drawing which illustrates by way of example an embodiment of this invention:

Figure 1 represents a bottle having its neck arranged with an embodiment of this invention.

Figure 2 is an enlarged detail in section of the bottle neck indicated in Figure 1 and with various portions named for facile identification.

Figure 3 is a modified form partly in section

showing the neck exterior at the drop break portion extended slightly.

Figure 4 is a form of neck provided with a modified exterior drop-break portion.

Similar reference characters refer to similar parts throughout the drawing.

In the construction shown in the drawing, 1, indicates in all the views the body proper of a bottle which has a typical shoulder 2 from which 3, a neck extends and terminates with a mouth plane 4. Screw threads such as are found moulded on bottles using screw caps are shown at 5, and the fender 6 is provided for acting as a stop for the cap and other purposes. In Figure 1 there is provided in the mouth of the bottle, a slanting or bevelled outflow 7 on the interior, to which is connected a barrel passage 8, and which is so arranged that it has an edge 9 that forms a restricting barrier to the flow of liquid from the bottle body. This barrier is preferably squared as indicated. In other figures, the similar parts are indicated with the same reference characters to assist in identifying them. In pouring the liquid from this bottle mouth in the usual manner, and holding it up so that the flow is very gradual and restricted, the barrier will afford some resistance and split the flow stream causing it to readily break into drops. As the broken stream reaches the bevel, it accelerates and as it reaches the mouth plane, it cuts the drops off and they flow off without any tendency to run down the bottle neck and drip thereon, which is particularly prevented by the elongated end portion 10 that extends exteriorly above the screw threads and is of less diameter than that of the screw threads.

The action of this mouth on the bottle is peculiar as it definitely makes a non-drip feature when liquids are poured through it, and while there is a cutting function on the drops that assists in giving it the power to make drops without dripping, it also has a quasi-capillary action that enables a drop to be caught up and caused to flow back into the bottle without dripping, if desired. It allows a control over the drops of liquid that are being poured out of the bottle. It has been also found that different liquids vary in their pouring action, due to their variable viscosity and other characteristics, and for this reason various other constructions are indicated in the different figures to meet these conditions. The other figures are self-explanatory.

The various containers may be made of glass or similar vitreous materials, or of other materials

suitable for liquids and liquid containers, as are now used or to be used in the future. Where the device that is outlined in this invention, is made separable, such may be made of any suitable material and attached in any convenient manner when placed in the bottle.

The normal pouring position of bottles is that of a horizontal but slightly tilted, and in such cases, the flow may be made to come out slowly, until there is a drop action, and the dropping can be controlled, drop by drop with the containers outlined in this application, and there is a complete absence of running-down of the stream on the side or body of the container.

The general action of drip-less feature of this invention operates as follows:—Referring to Figure 2, the bottle is tilted until the liquid in the bottle flows from the barrel passage 8, passing over point 80, and along angular pouring lip 7, to the edge 81. Capillary attraction then attaches the fluid to the face 82. The set-back 83 then prevents the fluid from contacting the elongated portion 10. This naturally prevents the fluid from flowing to the right angular rise 84 and threaded portion 5, thereby preventing the liquid flowing into the screw threads and thence down the outside surface of the bottle. When the bottle with its barrel passage 8 is brought up to an upright position, the point 80 cuts off the supply of fluid, which then flows over the angular portion 7. The width of the face 8 is always narrow enough to prevent the capillary attraction of the bottle material from being greater than the weight of a drop of the liquid to be poured. The upper portion of the neck where it overlaps, and is designated at 81, 82 and 83 is termed a "flange". The recess at 83 and 84, making the neck of the bottle restricted in diameter is termed "an annular groove". The space between the flange and the plane surface at 84 and 5 is termed a "drop-break" because the distance is sufficient to avoid permitting the drop of liquid to bridge over it and flow down the remainder of the outside surface of the bottle neck. The angular lip 7 and face 4, by tending to bring the drop of liquid back into the bottle, is termed a "drop slide", especially when the drop is not positioned sufficiently to fall over the edge 82 in the manner already described.

Many experiments have been made in the matter of this invention by the applicant, covering many types of bottles, and many different liquids, and it has been found that existing con-

ventional types of bottles do not provide this feature of non-dripping, so-called, and where the insertion of a make shift device for insertion in the bottle neck has been used, such have not proven to be of practical serviceability, as have been heretofore provided. It has also been unsatisfactory from a manufacturing point of view to avoid the construction of a bottle with this function that has not the arrangement homogeneously embodied in it, but since in the past 10 there was no such bottle provided with these features, such have not been heretofore embodied by bottle manufacturers, especially those of a vitreous nature. The features are shown incorporated in the bottle and afford the functions 15 that enable the manufacturers to provide same in it.

While several types of construction of this invention have been indicated in the drawing, it is not desired to limit this application for patent to 20 them, or in any other way, other than limited by the prior art, as it is appreciated that other forms of construction might be made that would use the same principles and come within the scope of the appended claim.

I claim:

In a bottle neck, the combination of a neck proper with an interior barrel or throat formed by the interior walls thereof, a mouth or orifice portion extending from the said walls having 30 walls angularly disposed with respect to and connected with the walls of the throat, a mouth plane disposed at right angles to the axis of the neck and extending outwardly therefrom to form the face a flange at the end portion of the neck, a 35 peripheral wall around the mouth plane and extending perpendicularly down therefrom to form the edge wall of the flange and away from the exterior wall of the throat, said peripheral wall being connected at right angles to the under surface wall of the flange, providing a set-back plane parallel to the mouth plane and inwardly limited with respect to the bottle neck by the exterior wall of the throat portion, said exterior wall of the throat portion being disposed at right angles 40 thereto and downwardly forming a restricted portion of the neck and spacing the flanged portion from the main body portion of the neck, the said main portion of the neck being enlarged and provided with an upper surface plane at right angles 45 to the exterior wall of the restricted portion, substantially as described.

HOWARD J. WHELAN.
